UNITED STATES PATENT OFFICE.

WILLIAM KARL KUBIN, OF NEW YORK, N. Y.

DESIGN FOR A BADGE.

SPECIFICATION forming part of Design No. 21,573, dated May 24, 1892.

Application filed January 7, 1892. Serial No. 417,312. Term of patent 7 years.

To all whom it may concern:

Be it known that I, WILLIAM KARL KUBIN, a citizen of the United States, residing at New York, in the county of New York and State of New York, have invented and produced a new and original Design for Badges; and I do hereby declare the following to be a full, clear, and exact description of the same, reference being had to the accompanying drawing, forming a part thereof.

The drawing represents a plan view of my design for a badge.

The essential feature of my design is a portrait of Christopher Columbus within a representation of a frame above a picture of ships upon a body of water, said picture being inclosed in a wreath.

The adjunctive features of my design are a shield at the top of the frame and a crown at the bottom, and a flag at one side of the frame and a banner at the other.

In the drawing the frame is designated by the reference-letter A and the wreath by the reference-letter B.

What I claim, and desire to secure by Letters Patent, is—

The design for a badge, as herein shown and described.

In testimony whereof I affix my signature in presence of two witnesses.

WILLIAM KARL KUBIN.

Witnesses:

WM. BONELLI,
W. K. DETWILLER.
